UNITED STATES PATENT OFFICE

2,572,230

FURNACE CLEANING SHOVEL

Ernest Williams, Kankakee, Ill.

Application March 15, 1948, Serial No. 21,472

3 Claims. (Cl. 294—53.5)

1

This invention relates generally to shovels, and more particularly to a shovel in which the scoop is adjustable relative to handle portions.

A primary object of this invention is to provide a shovel which is ideally constructed for use in cleaning out the fine ash accumulation from furnaces, both during the operation of the furnace and when the fire pot is empty, the cleaning being accomplished by the use of this improved shovel by manipulating the shovel through the fire door of the furnace.

Another object of this invention, ancillary to the preceding object, is to provide a shovel which may be adjusted so that the scoop may reach portions otherwise difficult of access, as for example portions immediately beneath the fire door.

Still another object of this invention is to provide an adjustable shovel in which the scoop may be shifted relative to the handle without employment of any mechanical means other than the mere deliberate forcing of these scoops to turn relative to the handle, improved frictional bearing means being provided to retain the scoop at any predetermined angular relationship with the handle.

Still another object of this invention, related to the foregoing objects, is to simplify the construction of adjustable shovels and to delete therefrom awkward and unsatisfactory latching means used in shovels proposed heretofore to retain the scoop in proper positional relationship relative to the handle.

And a last object to be mentioned specifically is to provide a shovel of this character which is relatively inexpensive and practicable to manufacture, which is simple and safe as well as convenient to operate, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawing which forms a material part of this application, and in which:

Figure 1 is a three dimensional view of the assembled tools;

Figure 2 is a vertical sectional view of the assembled shovel; and,

Figure 3 is a fragmentary transverse sectional view taken on a vertical plane through the line 3—3 in Figure 2.

Similar characters of reference designate similar or identical elements and portions through-

2

out the specification and throughout the drawing.

Referring now to the drawing in detail, it is proposed by this invention to provide a shovel having a scoop 10 with a sharpened rounded nose portion 12 and a heel portion which may include a vertical plate 14 integrally secured to the scoop as illustrated in the drawing.

10 A reinforcing plate 16 is welded to the central and lower part of the said heel portion, and this plate 16 has a neck 18 upstanding therefrom adjacent to the vertical plate 14. The scoop is apertured immediately beneath the neck 18 and an upstanding pipe 20 is welded to the neck 18 so that the lower end of the pipe 20 is adjacent to the lower edge of the scoop 10 and this pipe extends well above the top of the scoop.

15 The upper end of this pipe 20 has a collar 22 welded thereto and the sleeve 24 is freely mounted within the lower end of this tube 20. A handle 26 is bent as at 28 intermediate the length thereof and a portion 30 of the handle extends from the bend 28 through the tube 20 and is engaged with the sleeve 24 in any suitable manner.

20 25 A coiled spring 32 is compressed between the collar 22 and the sleeve 24 and between the portion 30 of the handle and the tube 20. The result of this construction is that the tube 20, collar 22, and indirectly the scoop 10, are preserved in frictional engagement with the handle, so that the handle may be forced to shift relative to the scoop but will retain its relative position unless deliberately forced out of this position by the operator. A preferred handle construction 30 includes a loop 34 on the outer end thereof, and it is preferred that the portion 30 shall be bent at substantially a right angle with the remaining portion of the handle, thus bringing the said remaining portion of the handle approximately parallel with the scoop 10, and the operator may at all times easily gage the disposition of the scoop relative to the horizontal even when the scoop is hidden from view.

25 35 The particular method of attaching the sleeve 24 to the lower end of the portion 30 of the handle illustrated in Figures 2 and 3, is of considerable importance inasmuch as this construction allows for absolute minimum cost of manufacture while allowing for tightening adjustment whenever required. The sleeve 24 is bevelled as indicated at 36 and the lower end of the handle is peened as at 38 so that satisfactory connection is made. It will be obvious that any operator having a minimum of mechanical skill will be 40 45 50 able to adjust the tightness of connection be-

tween the handle and the scoop, when this is necessary, by simply further peening the end of the handle. An adjustability is, therefore, provided with an absolute minimum of equipment.

The operation of this invention will be clearly understood from the foregoing description taken in connection with the drawing and with the above recitation of the objects sought to be achieved by this invention. In recapitulation, it need only be added that the improved adjustable shovel described herein is capable of being operated with the scoop 10 disposed at any angle in a plane normal to the portion 30 of the handle. In the light of the foregoing description, it will also now be clear that the shovel is completely free from mechanical latching means of the exposed type and that the shovel will achieve all the objects for which it is intended.

Minor variations may be made in the details of construction and proportionment of the various elements of this invention without departure from the spirit and scope thereof, which scope should be determined only as required by a proper interpretation of the terms used in the subjoined claims.

Having described the invention, what is claimed as new is:

1. A shovel comprising a scoop, a reinforcing plate on the heel of the scoop, an upstanding neck on said plate, an upstanding pipe fixed in said neck and extending above the top of said scoop, an elongated handle having a portion thereof extending through said pipe and having a bent portion at the upper end of the pipe, and a spring coiled between said first mentioned portion and said pipe and compressed between the

upper end of said pipe and the upset end of the handle.

2. A shovel comprising a scoop, a reinforcing plate on the heel of the scoop, an upstanding neck on said plate, an upstanding pipe fixed in said neck and extending above the top of said scoop, an elongated handle having a portion thereof extending through said pipe and having a bent portion at the upper end of the pipe, 10 said upper end of the pipe having an internal collar fixed thereto, the lower end of said handle having a sleeve thereon mounted for free movement within said pipe, and a coiled spring compressed between said collar and said sleeve, coaxially of and within said pipe.

3. A shovel comprising a scoop, an upstanding pipe rigidly supported on said scoop, an elongated handle having a portion thereof extending through said pipe and having a bent portion at the upper end of the pipe, 20 said upper end of the pipe having an internal collar fixed thereto, the lower end of the handle having a sleeve fixed thereon and mounted for free movement within said pipe, and a coiled spring compressed between said collar and said sleeve coaxially of and within said pipe.

ERNEST WILLIAMS.
